**HORIZONTAL PRESS AND METHOD OF
OPERATION, ESPECIALLY FOR FORMING
CAN BODIES**

Albert Clements, Hamilton, Ohio, assignor to The Minster Machine Company, Minster, Ohio, a corporation of Ohio

Filed Jan. 2, 1964, Ser. No. 335,096
9 Claims. (Cl. 72—456)

This invention relates to presses and is particularly concerned with a horizontal acting press and, more particularly still, is concerned with a novel supporting and guiding arrangement for the slide of a horizontal press.

Horizontal presses are known and, in general, comprise a press frame in which a slide is horizontally movable to operate dies mounted in the press and operable to perform working operation. Satisfactory guiding of the slide can be accomplished by the usual flat guide members or gibs in the press frame engaging the corners of the press slide. In other cases, however, support of this nature for the press slide does not provide the high degree of accuracy of guiding the press slide that is necessary for the particular dies being operated. For example, with work members having extremely thin side walls, such as cans for foods or beverages, the alignment of the punch with the die is critical to maintain the same wall thickness completely around the cans being formed in the press.

With the foregoing in mind, the present invention has as a primary object the provision of a greatly improved guiding arrangement for the slide of a horizontal press that provides for greater accuracy of guiding of the slide.

Another object of the present invention is the provision of a guiding arrangement for the slide of a horizontal press in which the accuracy of guiding by anti-friction bearings is obtained while the transverse loading imposed on the slide is absorbed by sliding bearing areas.

A still further object of the present invention is the provision of a guiding arrangement for a horizontally movable press slide in which the sliding bearing areas associated with the slide are maintained under light loads and thus do not wear rapidly.

A still further object of the present invention is the provision of an arrangement, in connection with a slidably guided horizontally movable press slide, which substantially equalizes the load on the sliding bearing surfaces that guide the slide as it reciprocates in the press frame.

Still a further object of this invention is the provision of a roller type supporting arrangement for a slidably supported horizontally movable press slide which is adaptable to the support of press slides of various sizes.

Still another object of the present invention is the provision of a novel can forming press in which a superior product can be made.

The foregoing objects, as well as still other objects and advantages of the present invention, will become more apparent upon reference to the following specification taken in connection with the accompanying drawings, in which:

FIGURE 1 is a side elevational view of a horizontal press having the present invention incorporated therein and partly broken away to show operative parts of the press;

FIGURE 2 is a plan view of the press;

FIGURE 3 is an end view, looking in from the right end of FIGURE 1;

FIGURE 4 is a fragmentary sectional view showing a typical die used in a work operation in the press;

FIGURE 5 is a transverse sectional view through the press, and is indicated by line 5—5 on FIGURE 1;

FIGURE 6 is a positional plan section, indicated by line

2

6—6 on FIGURE 5, and showing the manner in which the connecting rods which actuate the slide can be adjusted in length;

FIGURE 7 is a sectional view showing how an ejector mechanism can be arranged on the press slide for ejecting work pieces that have been formed on punches carried by the slide.

Referring to the drawings somewhat more in detail, the horizontal press embodying the present invention comprises a stationary frame 10 within which a slide member 12 is horizontally movable. The slide member 12 is adapted for carrying elements 14 that cooperate with elements 16 of a punch and die set for forming can bodies from a sheet of stock 18 fed laterally through the opening 20 in the press frame. The formed work members are ejected when slide 12 retracts toward the left and the ejected can bodies drop on a conveyor 22 extending laterally through another opening 24 in the press frame.

The slide 12 has spaced connecting rods 26 connected thereto by the transverse pivot means 28. At their ends opposite the slide 12, the connecting rods 26 are connected to the crank pins 30 of a crankshaft 32 journaled on its line bearings in the frame 10 of the press. One end of the crankshaft 32 carries a large drive gear 34 that meshes with a pinion 36 on a transverse shaft 38 journaled in the press frame, and which shaft also carries a flywheel-pulley 40 over which drive belts 42 are entrained. Drive belts 42 are also entrained over a pulley 44 mounted on the output shaft of an electric drive motor 46.

Turning now to FIGURE 5, it will be seen therein that slide 12 is slidably guided between the side walls 48 and 50 of press frame 10 by gib means extending parallel to the direction of slide movement. At the bottom of the press slide 12 are the angular elements 52 mounted on the side walls of the press frame. The press slide at its bottom corners carries a rail 54 slidably engaging the top of the adjacent angular rail member 52 of the press frame. The slide also carries an elongated rail 56 engaging the inwardly facing corner of the adjacent angular rail 52 of the press frame. Member 56 has an inclined back wall and is adapted for being adjusted laterally toward and away from rail 52 by a wedge member 58 which bears between member 56 and the portion 60 of the slide that forms a rigid backing up shoulder for member 58. Suitable bolts are provided for clamping members 56 and 58 in their adjusted positions so that the slide is confined with respect to lateral movement between the angular elements 52 mounted on the press frame side walls.

A similar arrangement is provided at the top of the press slide except that the elements 62 which are mounted on the press frame side walls and which engage the upper corners of the slide are themselves adjustably mounted in the press frame. Elements 62 extend vertically along the insides of the side walls 48, 50 to the tops thereof and then have laterally extending portions 64 that overlay the tops of the side walls. Bolt means 66 are provided for moving elements 62 downwardly into proper engagement with the upper corners of the press slide, while bolt means 68 are provided for clamping the elements 62 in their adjusted positions.

The aforementioned gibbing arrangement thus provides for accurate sliding support of the press slide in the press frame. The sliding bearings thus formed require the maintaining of an oil film between the interengaging surfaces, and an oil film of this nature can be maintained either by a continuous supply of oil under pressure to the region between the surfaces, or by merely supplying lubricant to the surfaces and permitting it to be dragged along as the slide reciprocates. In either

case, some slight clearance must be permitted between the surfaces to allow the necessary oil film to be carried therein as the slide reciprocates. Because of this slight clearance, it follows that the press slide can deflect slightly laterally under load, and, furthermore, since the entire weight of the press slide is carried on the lower gib, the tendency is for the slide to drop downwardly slightly and the lower gib will wear more rapidly than the upper gibs.

The present invention proposes to eliminate the aforementioned tendency for the slide to deflect laterally or for the lower gib regions to wear more rapidly than desired, by supporting the slide so that the aforementioned gib surfaces have mainly to absorb lateral loading on the press slide and do not have to assume the entire guiding and supporting of the slide at all times.

The additional supporting of the slide is accomplished, in brief, by providing the press frame with rails along the top, extending parallel to the direction of movement of the slide, and by mounting rollers on the slide resting on the aforementioned rails. Suitable adjusting means is provided between the rollers and the slide so that the rollers support the slide weight exactly, thus substantially completely relieving the gibs of load except upon lateral deflection of the slide during a working operation.

The roller arrangement for supporting the slide will be seen in FIGURES 1, 2, 3 and 5. The rails or tracks for the rollers are indicated 70 and may be adjustably mounted on the upper ends of the gib members 62 as by screws 72. An advantage of this arrangement is that the rails or tracks 70 will stay in exact parallelism with the lower guiding surface of gibs 62 at all times.

The rails or tracks 70 are engaged by spaced rollers 74 which are preferably in the form of antifriction bearings and which rollers are supported on stud members 76 fixed in a rigid pan-like frame 78 that extends over the top of the slide from side to side of the press frame. The rollers 74 are spaced longitudinally of the slide, as will be seen in FIGURES 1 and 2, and the center of gravity of the slide, including the punch devices mounted thereon will be disposed in the region between the longitudinally spaced rollers whereby the slide is supported without any tendency to tilt.

Frame 78 has sleeve elements 80 fixed thereto through which rods 82 slidably extend. The rods 82 are threaded at their lower ends into the bosses 84 fixed to the top of the press slide. Rods 82 at their upper ends carry the adjustable nuts 86 and bearing between washers beneath the nuts and the upper face of small bosses on pan member 78 are compression springs 88. Adjustment of nuts 86 is effective for causing rollers 74 to pick up exactly the weight of the slide. This can be done, for example, by placing indicators at four positions at the bottom of the slide as close to the slide corners as possible and thereafter adjusting nuts 86 until the indicators indicate that the weight of the slide has been picked up by rollers 74. After this adjustment has been made, substantially the entire weight of the slide is carried by rollers 74 and the tracks 70 therebeneath, and the gib arrangement has only to provide support for the slide when it is deflected laterally by working loads imposed thereon.

The connecting rods 26 which actuate the slide are adjustable in length as is disclosed in FIGURE 6 wherein it will be seen that each connecting rod includes a threaded portion 81 to which is keyed a bevel gear that meshes with a bevel pinion 85 on a transverse shaft 87 adapted for being reversibly actuated by a ratchet wrench 89. Both connecting rods are adjusted simultaneously in this manner so that the stroke of the slide can be changed when desired.

When the slide carries elements 14 in which the work pieces will be formed, it is necessary to strip the work pieces from the elements 14 when the slide retracts, and this is done by a mechanism illustrated in FIGURE 7. In this figure the knock-out rods extending through the

elements 14 are designated at 90. These rods are connected to a cross-head 92 which is engaged by arm 94 of a bell crank lever 96 pivoted on shaft 98 on the press slide. Lever 96 has another arm 100 that carries a roller 102 engaging one face of a cam bar 104 adjustably mounted on the press frame by the screw arrangement 106. The slide also carries a frame 108 in which is mounted a cam bar back-up roller 110 so the cam bar will be supported when roller 102 rides up the incline 112 of the cam bar thereby to actuate the knock-out rods 90 to eject work pieces.

It will be understood that the particular punch and die set illustrated in the drawings is merely exemplary of many types of tools that can be placed in the press and that the present invention is concerned principally with the supporting and guiding of the horizontal slide so that punch and die sets and the like requiring accurate guiding of the movable slide can be operated in the press. The can forming tools illustrated are a particular example of tools that are particularly benefited by the provision of a press arrangement and slide supporting arrangement of the nature disclosed herein.

FIGURE 4 shows more in detail the construction of dies for use in the press.

Slide 12 carries the elements 14 which cooperate with elements 16 to blank out a discs from stock 18. Elements 16 include the forming punch portions 17 that form the blanked out discs in cavities 19 of elements 14. Draw ring or pressure ring 21 of each element 16 is supported by pressure pins 23 that extend through bed portion 25 of the press and are connected to conventional cushion means (not shown). The bottom of each cavity 19 is formed by a member 91 on the end of the pertaining knock-out rod 90.

The die means are advantageously arranged as shown in FIGURE 3 along a diagonal extending across the press bed.

The press according to the present invention has closed sides, as opposed to the usual open gap type press usually employed for can presses and is thus subject to less deflection than conventional can presses. This feature, in combination with the feature of the guiding of the slide described above, results in the forming of can bodies with uniform wall thickness.

The machine can be controlled in any desired manner as, for example, by way of a control pedestal 110 connected to the press by way of a cable 112. A control limit switch L.S. could also be provided driven from the crankshaft by a chain 114 and included in the control system.

A particular benefit of the counter balance arrangement, in addition to supporting the slide at exactly the proper position, is that the weight of the slide is lifted from the lower guide ways and this prevents squeezing out of the oil from the lower guiding ways, particularly when the slide is stationary. The squeezing out of the oil from these surfaces can result in extremely rapid wear thereof, and which wear would probably be ununiform from one end of the guiding surfaces to the other so that compensation for the wear would be difficult. By the arrangement of the present invention, the oil is not squeezed out from the guide surfaces so that as soon as the slide commences to move it will be supported on a proper oil film at each corner.

It will be understood that this invention is susceptible to modification in order to adapt it to different usages and conditions; and accordingly, it is desired to comprehend such modifications within this invention as may fall within the scope of the appended claims.

What is claimed is:

1. In a horizontal press, the improvement comprising: a press frame, a press slide in the frame, guide means in the frame for guiding and supporting the press slide, and counter-balancing means connected between the frame and the press slide for supportably counter-balancing at least a portion of the weight of said slide.

2. In a horizontal press, the improvement comprising: a press frame, horizontally extending guide means in the press frame, a slide horizontally movable in the press frame, the slide engaging and being supported by the guide means, horizontal rails carried by the press frame, a carrier movable along said rails, and resilient means connected between the carrier and the slide for supportably counter-balancing at least a portion of the weight of said slide.

3. In a horizontal press, the improvement comprising: a press frame, a slide horizontally movable in said press frame, horizontally extending guide means in the frame engaging the corners of the slide for guiding it during its movement in the frame, horizontal rails extending along the top of the frame, a carriage having rollers engaging said rails, and adjustable resilient means connecting said carriage with said slide for counter-balancing the weight of said slide whereby extremely accurate guiding of said slide by said guide means is obtained.

4. In a horizontal press, the improvement comprising: a press frame, a slide horizontally movable in said press frame, horizontally extending guide means in the frame engaging the corners of the slide for guiding it during its movement in the frame, horizontal rails extending along the top of the frame, a carriage having rollers engaging said rails, and adjustable resilient means connecting said carriage with said slide for counter-balancing the weight of said slide whereby extremely accurate guiding of said slide by said guide means is obtained, said adjustable resilient means comprising rods connected to the slide and extending vertically upwardly through the carriage, and springs balancing between the top of the carriage and the upper ends of said rods for thrusting the rods upwardly and thereby counter-balancing weight of the said slide, said rods having nuts threaded to the upper ends thereof to provide adjustable abutments for said springs.

5. In a press for making can bodies, the improvement comprising: a horizontal press, said press having sides with openings therein through which strip stock is fed for being formed into can bodies by die means carried in the press, a slide horizontally movable in the press, gib means on the insides of said walls slidably engaging the corners of said slide, rails on the top of the press parallel with said gib means, a carriage on top of the press having rollers engaging said rails, rods connected to the slide and extending upwardly through the carriage, nuts on the upper ends of said rods, and springs balancing between the nuts and the top of the carriage to counter-balance the weight of the slide during its horizontal movement along said gib means.

6. In a horizontal press for forming can bodies, the improvement comprising: side frame members, openings in said side frame members for admitting strip stock for being formed into can bodies, a slide horizontally movable between said side members, gib means on the side members slidably engaging the corners of said slide for guiding it in its horizontal movement, a bed member connected between said side members, can body forming die means mounted on said slide and said bed member operable for forming can bodies as the slide reciprocates, rails on the tops of the side members parallel with said gib means, a carriage positioned over said slide, rollers fixed to said carriage and engaging said rails, rods fixed to said slide and extending upwardly through said carriage, adjustable elements on the upper ends of said rods, and springs balancing between the top of the carriage and the under sides of said elements for counter-balancing the weight of said slide.

7. In a horizontal press for forming can bodies, the improvement comprising: side frame members, openings in said side frame members for admitting strip stock for being formed into can bodies, a slide horizontally movable between said side members, gib means on the side members slidably engaging the corners of said slide for guiding

it in its horizontal movement, a bed member connected between said side members, can body forming die means mounted on said slide and said bed member operable for forming can bodies as the slide reciprocates, rails on the tops of the side members parallel with said gib means, a carriage positioned over said slide, rollers fixed to said carriage and engaging said rails, rods fixed to said slide and extending upwardly through said carriage, adjustable elements on the upper ends of said rods, and springs balancing between the top of the carriage and the under sides of said elements for counter-balancing the weight of said slide, said press including a rotatable crankshaft carried by said side members at the end opposite said bed member, and adjustable connecting rods connecting said crankshaft with said slide.

8. In a horizontal press for forming can bodies, the improvement comprising: side frame members, openings in said side frame members for admitting strip stock for being formed into can bodies, a slide horizontally movable between said side members, gib means on the side members slidably engaging the corners of said slide for guiding it in its horizontal movement, a bed member connected between said side members, can body forming die means mounted on said slide and said bed member operable for forming can bodies as the slide reciprocates, rails on the tops of the side members parallel with said gib means, a carriage positioned over said slide, rollers fixed to said carriage and engaging said rails, rods fixed to said slide and extending upwardly through said carriage, adjustable elements on the upper ends of said rods, and springs balancing between the top of the carriage and the under sides of said elements for counter-balancing the weight of said slide, the can bodies being retained in the die means carried by the slide, knock-out members for ejecting the can bodies, and means operated by retracting movement of said slide away from said knock-out members.

9. In a horizontal press for forming can bodies, the improvement comprising: side frame members, openings in said side frame members for admitting strip stock for being formed into can bodies, a slide horizontally movable between said side members, gib means on the side members slidably engaging the corners of said slide for guiding it in its horizontal movement, a bed member connected between said side members, can body forming die means mounted on said slide and said bed member operable for forming can bodies as the slide reciprocates, rails on the tops of the side members parallel with said gib means, a carriage positioned over said slide, rollers fixed to said carriage and engaging said rails, rods fixed to said slide and extending upwardly through said carriage, adjustable elements on the upper ends of said rods, and springs balancing between the top of the carriage and the under sides of said elements for counter-balancing the weight of said slide, the can bodies being retained in the die means carried by the slide, knock-out members for ejecting the can bodies, and means operated by retracting movement of said slide away from said knock-out members, said last-mentioned means comprising a lever pivoted to the slide having one arm operatively connected with said knock-out means, and cam means adjustably connected by said press operable for actuating said lever in response to retracting movement of said slide.
